UNITED STATES PATENT OFFICE.

FREDERICK J. BALCOM, OF BINGHAMTON, NEW YORK, ASSIGNOR TO UNITED SHOE MACHINERY CORPORATION, OF PATERSON, NEW JERSEY, A CORPORATION OF NEW JERSEY.

MACHINE FOR OPERATING UPON HEELS.

Application filed March 5, 1920. Serial No. 363,494.

To all whom it may concern:

Be it known that I, FREDERICK J. BALCOM, a citizen of the United States, residing at Binghamton, in the county of Broome and State of New York, have invented certain Improvements in Machines for Operating Upon Heels, of which the following description, in connection with the accompanying drawings, is a specification, like referring characters on the drawings indicating like parts in the several figures.

This invention relates to apparatus for operating upon heels, it concerning more particularly heel-pricking machines. These are commonly provided with a feeding instrumentality, as an oscillatory lever, which is adapted to carry a heel into co-operation with the mechanism, as the pricking awls and clamping follower, by which it is to be acted upon. Sometimes heels are over-fed by the lever, they being advanced by their momentum beyond the point at which its oscillation is reversed to return for the succeeding feeding operation. In such cases the fork, which centers the heel before it is clamped for pricking, may not engage it properly, causing it to be so held that the awls enter incorrectly, or even breaking the fork. An object of this invention is to prevent this over-feeding action, insuring the perfect delivery of each heel to the mechanism which is to operate upon it.

A feature of the invention, leading to the attainment of the above objects, consists in means for feeding a heel over a support to the mechanism by which it is to be acted upon, combined with novel means movable along the path of the heel in the operation of the machine feed for limiting the feeding movement of said heel, which is thus retained in the desired position. This movement-limiting means may have a bodily movement with the feeding means, and, regardless of the manner of support of the heel, I preferably move the limiting means out of the path of the heel after it has performed its limiting function, it being connected to a relatively fixed point to control it in this and other actions. The movement-limiting means is shown as yieldable in the direction of feed, it thereby being adapted to accommodate itself to the work, especially in disengagement. In the machine for pricking heels which I have illustrated, the feeding lever has associated means for tem-

porarily retaining the heel fed in proximity to it. This retaining means I prefer to provide in the form of an arm, pivoted to the lever and articulated to a fixed portion of the machine by a link. This arm or retaining means, in the reverse movement of the feeding lever when the heel is released, may be made yieldable to facilitate this by the provision of a slot-and-pin connection between the lever and the arm, with the connection under the influence of a spring.

The heels operated upon by the machine may differ considerably in their dimensions, and, to cause the different sizes to be acted upon properly by the movement-limiting means in its movement, a further feature of my invention resides in adjustable means arranged to permit the relative movement between the feeding means and the limiting means to be determined. By this expedient the limiting effect may be exerted at the right point, whatever the size of the heel fed. Herein this variation is provided in the length of the limiting means, and with this means connected to a relatively fixed point, the length of the connection should also be changed. The heel-pricking machine which I have illustrated has its retaining arm joined to the feed-lever constructed in sections variable with respect to one another, and with the connecting link for the arm also preferably thus arranged.

My invention is illustrated in the accompanying drawing as applied to a heel-pricking machine such as is disclosed in Patent No. 1,234,384, dated July 24, 1917, and issued to J. H. Pope.

Fig. 1 of the drawing being a partial transverse section through such a machine, taken just at one side of the feeding mechanism; and

Fig. 2, an enlarged detail view of the retaining arm and its connecting link.

Across the base 10 of the machine extends a supporting surface or way 12, along which heels, indicated at H, are fed to the right as the machine is viewed in Fig. 1 of the drawing, from a receiving position, shown in dotted lines, in which they are placed by the operator, to a position in which they are acted upon by the pricking mechanism, this appearing in full lines. In the latter position they are alined with the openings of a templet 14, through which openings pass pricking awls mounted upon a reciprocatory

block 16. In the pricking position the work is centered for the operation, prior to its clamping against the templet by the follower (not shown), through the agency of a 5 fork 18 mounted to slide vertically in a frame 20 rising from the base. This fork is reciprocated by suitable mechanism, as in the patent previously mentioned, from the elevated position illustrated, in which 10 the work is fed, to the centering position, in which the fork contacts with the heel to position it. Pivoted at 22 upon the frame 20 is a feeding lever 24, oscillated by a link 26, bell-crank 28 and slide 30, all as described 15 in the Pope patent. The termination of the forward stroke of the feeding lever may be adjusted by a variable pivotal connection 32 between the bell-crank lever 28 and the slide 30, and also by changing the normal 20 angle of a section 34 of the lever 24 by means of a screw 36, so that its contact end 38 advances each heel supplied by the operator to the desired pricking position. At this time, if the heel remains in contact 25 with the feeding lever, it is substantially in correct alignment with the templet, and is so related to the fork that the juncture of the arms of the latter lies at or near a vertical axis through the heel, so that, when the 30 fork descends, it may readily move the heel to the exact point desired with relation to the templet. There may, however, be sufficient impetus imparted to the heel by the lever to throw it beyond the stopping point, 35 in which case the end of a fork-arm may engage the top of the heel and clamp it out of the true pricking position, or the fork may be injured by the contact. This I prevent by the movement-limiting means now to be 40 described.

Extending horizontally from the side of the feeding lever portion 34, at a point above the tops of the heels which it feeds, is a pivot pin 40, preferably surrounded by an 45 anti-friction roll 42. This roll operates in a slot 44 extending longitudinally near one end of an arm 46. Near the opposite end the arm is articulated at 48 to a link 50, the other extremity of the link being pivoted 50 at 52 to a relatively fixed point, as a portion of the frame 20. Preferably, the arm 46 is held yieldably, with the bottom of the slot 44 against the roll 42, by a helical spring 54 uniting the pin 40 with that furnishing the articulation 48. When the feeding lever is in the receiving position shown in dotted lines, the arm 46 is raised by the pull of its connecting link 50 into a position considerably above the path of the heels. 55 As the feeding lever oscillates to carry the heel to the pricking position, the arm 46 advances with it, but more slowly, since it is at the same time directed downwardly by its link. The lengths of the arm and link and their pivotal connections are so

related that when the lever 24 reaches its extreme of feeding movement, the lower curved extremity 56 of the arm 46 comes into contact with or in close proximity to the upper portion of the side of the heel 70 opposite that upon which the portion 38 of the lever bears. Because of the engagement of the arm with this opposite side of the heel, it cannot be moved by its momentum beyond the point at which it may be correctly engaged by the fork 18. So, when this descends, its centering contact with the heel is assured. Upon reverse movement of the feeding lever, in preparation for the advance of the succeeding heel, the contact face 75 56 is raised above and out of the path of the heel, and, if the end drags over the side of the heel, the spring 54 will yield, avoiding interference with the position of the heel, and doing away with the possibility of 80 breaking the arm or its connections. 85

To properly position heels having different transverse dimensions with reference to the operating mechanism, not only must the feeding lever be adjusted, as by the pivotal connection 32 and the angular relation of its end portion 34, but also the arm 46 must be correspondingly adjusted, but in the opposite direction. For this purpose, said arm is provided with an end section 58, having in it a longitudinal slot 60, through which extend screws 62 threaded into the main portion of the arm and serving to clamp the section 58 by the contact of their heads with it. The controlling link 50 is similarly variable in length, it having a lower end section 64, into which are threaded screws 66 passing through a longitudinal slot 68 in the body portion of the link. To adjust the arm and link for any particular size of heel to be operated upon, after the lever portion 34 has been arranged to give the desired feeding stroke and with this lever portion in its extreme heel-advancing position, the securing screws of the end sections of the arm and link are both loosened, the surface 56 carried into correct relation with the heel, and the sections clamped by their screws. 100 105

Having described my invention, what I 110 claim as new and desire to secure by Letters Patent of the United States is:

1. In a machine for operating upon heels, operating mechanism, a heel-support, movable heel-locating means co-operating with the support and operating mechanism, means for feeding a heel over the support to the operating mechanism, and means movable in the operation of the machine along the path of the heel for limiting the feeding movement of the heel to the field of action of the locating means. 115 120 125

2. In a machine for operating upon heels, operating mechanism, a heel-support, means for feeding a heel over the support to the 130

- operating mechanism, and means movable with the feeding means and independently thereof in the direction of feed for limiting the feeding movement of the heel.
- 5 3. In a machine for operating upon heels, operating mechanism, a heel-support, and means for feeding a heel over the support to the operating mechanism, said feeding means consisting of a plurality of members 70
10 contacting with the heel at separated points and traveling with the heel in its advance, one of said members being movable toward and from the support.
4. In a machine for operating upon heels, 80
15 an operating mechanism, a member for feeding a heel to the operating mechanism, a member limiting the feeding movement of the heel, and means for moving the limiting member in the direction of advance of the
20 heel and into and out of the path of said heel.
5. In a machine for operating upon heels, an operating mechanism, a member for feeding a heel to the operating mechanism, and 85
25 a bodily movable member connected to the feeding member and to a relatively fixed point for limiting the feeding movement of the heel.
6. In a machine for operating upon heels, 90
30 operating mechanism, a heel-support, means for feeding a heel over the support to the operating mechanism, and means yieldable in the direction of feed for limiting the feeding movement of the heel.
- 35 7. In a machine for operating upon heels, operating mechanism, a heel-support, means for feeding a heel over the support to the operating mechanism, and means mounted to yield bodily upon the feeding means for 100
40 limiting the feeding movement of the heel.
8. In a machine for operating upon heels, an operating mechanism, a member for feeding a heel to the operating mechanism, and a member connected to the feeding member 105
45 and to a relatively fixed point for limiting the feeding movement of the heel, one of the connections being movable longitudinally of the limiting member.
9. In a machine for operating upon heels, 110
50 an operating mechanism, a member for feeding a heel to the operating mechanism, a member connected to the feeding member and to a relatively fixed point for limiting the feeding movement of the heel, the connection of the limiting member to the feeding means being movable, and a spring acting upon such movable connection.
10. In a heel-pricking machine, awl mechanism, a feeding lever for advancing a heel to the awl mechanism, and means arranged to temporarily retain the heel in proximity to the feeding lever. 115
55
11. In a heel-pricking machine, awl mechanism, a feeding lever for contact with a heel to advance it to the awl mechanism, mov- 120
60
- ing an arm pivoted upon the feeding lever for co-operation with the heel.
12. In a heel-pricking machine, awl mechanism, a feeding lever for contact with a heel to advance it to the awl mechanism, and an arm pivoted upon the feeding lever and arranged to contact with the heel at the opposite side from the feeding lever. 70
75
13. In a heel-pricking machine, awl mechanism, a feeding lever for contact with a heel to advance it to the awl mechanism, an arm pivoted upon the feeding lever for contact with the heel, and a link articulated to the arm and to a relatively fixed portion of the machine. 80
14. In a heel-pricking machine, awl mechanism, a feeding lever for contact with a heel to advance it to the awl mechanism, and means to retain the heel in proximity to the feeding lever during the advance of said lever, said means being arranged to yield upon reverse movement of the lever. 85
90
15. In a heel-pricking machine, awl mechanism, a feeding lever for contact with a heel to advance it to the awl mechanism, and an arm pivoted upon the feeding lever for contact with the heel, there being a slot-and-pin connection between the arm and lever. 95
100
16. In a heel-pricking machine, awl mechanism, a feeding lever for contact with a heel to advance it to the awl mechanism, an arm pivoted upon the feeding lever for contact with the heel, there being a slot-and-pin connection between the arm and lever, and a spring exerting its force upon the connection. 105
110
17. In a heel-pricking machine, awl mechanism, a feeding lever for contact with a heel to advance it to the awl mechanism, an arm pivoted upon the feeding lever for contact with the heel and being provided with a longitudinal slot, a pin fixed to the lever and entering the slot, and a spring connecting the pin and arm. 115
120
18. In a machine for operating upon heels, operating mechanism, a heel-support, means for feeding a heel over the support to the operating mechanism, movable means for limiting the feeding movement of the heel, and adjustable means arranged to permit the relative movement between the feeding means and the limiting means to be determined. 125
130
19. In a machine for operating upon heels, operating mechanism, a heel-support, means for feeding a heel over the support to the operating mechanism, movable means for limiting the feeding movement of the heel, and adjustable means arranged to permit the movement of the limiting means to be determined. 120
125
20. In a machine for operating upon heels, operating mechanism, means for feeding a heel to the operating mechanism, mov- 120
125

- able means connected to the feeding means for limiting the feeding movement of the heel, and means arranged to permit the length of the limiting means to be varied.
21. In a machine for operating upon heels, operating mechanism, a member for feeding a heel to the operating mechanism, a member movable into contact with the heel to limit its movement, connections between the limiting member and a relatively fixed point, and means arranged to permit the normal relation of the connections to be varied.
22. In a machine for operating upon heels, operating mechanism, a member for feeding a heel to the operating mechanism, a movable member co-operating with the heel to limit its movement, a movement-modifying member connecting the limiting member to a relatively fixed point, and means arranged to permit the length of the connecting member to be varied.
23. In a heel-pricking machine, awl mechanism, a feeding lever for advancing a heel
- to the awl mechanism, and an arm pivoted upon the feeding lever for co-operation with the heel, said arm being in sections variable in their relation to one another.
24. In a heel-pricking machine, awl mechanism, a feeding lever for contact with a heel to advance it to the awl mechanism, an arm pivoted upon the feeding lever for contact with the heel, and a link articulated to the arm and to a relatively fixed portion of the machine, said link being in sections variable in their relation to one another.
25. In a heel-pricking machine, awl mechanism, a feeding lever for contact with a heel to advance it to the awl mechanism, an arm pivoted upon the feeding lever for contact with the heel, and a link articulated to the arm and to a relatively fixed portion of the machine, the arm and link being in sections variable in their relations to one another.

In testimony whereof I have signed my name to this specification.

FREDERICK J. BALCOM.
